UNITED STATES PATENT OFFICE.

MARTIN ZAWISTOWSKI, OF BROOKLYN, NEW YORK.

CLOTH-CUTTING MACHINE.

1,378,162.

Specification of Letters Patent. Patented May 17, 1921.

Application filed August 7, 1919. Serial No. 315,832.

To all whom it may concern:

Be it known that I, MARTIN ZAWISTOWSKI, a citizen of the United States, and a resident of Brooklyn, in the county of Kings and State of New York, have invented certain new and useful Improvements in Cloth-Cutting Machines, of which the following is a specification.

This invention is an improvement in cloth cutting machines of the motor driven reciprocating knife type. Such machines require frequent sharpening of the knife which is usually done by the use of an emery stick. A great deal of time is saved if this sharpening can be done while the knife is in the machine but it is necessary to move the guard away from its normal position before this can be done. The guard ordinarily carries the presser foot which is adjusted vertically in accordance to the thickness of the material being cut and a saving of time is effected if the presser foot can be returned to position after sharpening without necessitating readjustment. It is also frequently necessary to remove the knife and insert a new one, and inspect, clean, adjust, or oil the knife operating mechanism.

In my improved construction I provide a cover plate for the knife operating mechanism which may be readily moved to operative or inoperative position without necessitating the use of any tools. There is also provided a knife guard and presser foot adjustably secured to this cover plate so that both may be moved to inoperative position with the cover plate and the knife edge as well as the driving connections exposed for cleaning, oiling, adjusting, or sharpening operation. My improved presser foot is so constructed that when in operative position it engages with the material at both sides of the cutting edge but when moved to inoperative position, travels in a direction at right angles to the plane of the knife and to a point spaced a considerable distance from said plane so as not to interfere in any way with the use of the emery stick or other knife sharpening apparatus. In my improved construction, the cover plate which carries the guard and presser foot is mounted to swing about an axis preferably coincident with the axis of the rotary driving member of the knife and the presser foot

itself is formed of two pivotally connected sections, one of which may be swung outwardly and forwardly in respect to the other so that the presser foot as a whole may move laterally during the pivoted or swinging movement of the cover plate about its horizontal axis.

As a further important feature, I mount the motor and the axis of the rotary driving member for the knife slightly to the right of the plane of the knife so that the operator's view of the goods directly in front of the knife is substantially unobstructed. This also permits the power of the motor to be applied more effectively during the down-stroke of the knife when the main cutting operation takes place. My invention involves various other important features which will be referred to more particularly in connection with the following detailed description of one form which my invention may assume, and which is illustrated in the accompanying drawings.

In these drawings:

Fig. 1 is a side elevation.

Fig. 2 is a front elevation.

Fig. 3 is a view similar to Fig. 2 but with the cover plate, guard, and presser foot removed, and indicated in dotted lines in inoperative position.

Fig. 4 is a horizontal section showing the presser foot in plan, said section being taken on the line 4-4 of Fig. 5.

Fig. 5 is a central longitudinal section of the base.

Fig. 6 is a perspective view of the inner side of the upper part of the cover plate.

Figs. 7 and 8 are perspective views of the presser foot, shown in open and closed positions, and

Fig. 9 is a perspective view of the throat plate.

The machine in common with others of the same general type includes a base 10 adapted to be moved along the table beneath the goods to be cut, a standard 11 rigidly supported thereby, an electric motor 12, mounted on the standard, a reciprocating knife driven by the motor and guided by the standard 13, a knife guard 14 disposed substantially parallel to the knife, a presser foot 15, carried by the knife guard, and a handle 16 for propelling and guiding the machine. This

handle may also carry the switch 17 for controlling the motor current.

In my improved machine the center of the motor is positioned slightly to the right hand side of the plane of the knife (viewed from the handle end) and the drive shaft 18 is disposed horizontally. Secured to this shaft is a crank disk 19 having mounted thereon a pitman or connecting rod 20. The upper end of the knife 13 is bolted or otherwise rigidly secured to a lug 21 carried by a slide 22 to which the pitman or connecting rod 20 is pivotally secured. The slide 22 is mounted for direct vertical movement in a direction parallel to the plane of the knife and is held against rotation, turning, or lateral movement. As shown, the motor casing has a stationary guide rod 23 encircled by the slide and acting as a guide for the latter and the slide has a laterally extending flange 24 to which the connecting rod is secured and which engages with an adjustable guide member 25. The engaging surface of the flange 24 of the slide and the guide member 25 is such as to hold the slide against any tendency to rotary motion about the guide rod 23. For instance, the guide member 25 may have a V-groove receiving a chamfered edge on the flange 24. The guide member is secured to the casing by a pair of screws 26 mounted in slots or made with sufficient free play to permit of a very slight adjustment toward and from the slide, such adjustment being secured by adjusting screws 27 projecting laterally through a flange 28 on the casing.

The casing has an annular flange 29 encircling the crank disk and spaced therefrom and to this flange is secured the cover plate 30. The cover plate has an inwardly extending cylindrical flange 31 as shown particularly in Fig. 6, and this flange has slots or grooves 32 extending circumferentially thereof to receive screws 33 carried by the flange 29 of the casing. These hold the cover plate in position but at the same time permit a limited swinging movement of the cover plate about the center of the casing flange 29 which is the axis of the driving member 19. The flange 31 of the cover plate also has a pair of sockets or recesses 34 adapted to receive a spring pressed ball 35 carried by the casing flange 29. This ball and its spring may be retained in a housing cap 36 screwed into the casing flange and the sockets or recesses 34 should be so positioned that the ball will enter one when the cover plate is in operative position as shown in Fig. 3 and will enter the other when the cover plate is moved laterally to the dotted line position indicated in Fig. 3. Thus the cover plate will be automatically locked in either normal position or in the displaced position exposing the mechanism and knife edge. For sharpening a knife, inserting a new one, or oiling

and cleaning the driving mechanism, it is ordinarily sufficient to merely swing the cover plate aside but it will be apparent that the cover plate may be entirely removed by the removal of the screws 33 and the ball cap 36. The cover plate 30 is of such shape that it closely fits the lower or extending portion of the casing inclosing the driving parts and the lower portion 37 of its front wall lies in the plane in advance of the cutting edge of the knife.

Adjustably secured to the cover plate is the guard 14. This may be of any suitable character and may be clamped in position in any suitable manner. Merely as a suitable example, I have shown the cover plate provided with a slotted projection 38 receiving the substantially square rod 14 constituting the guard, and have shown a set screw 39 for locking the guard rigidly to the cover plate. It will of course be evident that any other suitable means may be employed for locking the two together and permitting of the vertical adjustment of the guard to the desired elevation in respect to the thickness of the material being cut.

The guard at its lower end carries the presser foot 15. This is illustrated as comprising two sections 40 and 41, the former rigidly secured to the guard and held against rotary or longitudinal movement. This rigid section has forwardly and rearwardly extending projections 42 and 43 presenting a curved undersurface for resting on the goods and holding them down as the machine advances. The other section 41 of the presser foot has a rearwardly projecting finger 44 which when in normal position lies substantially parallel to the finger portion 42 of the other presser foot section but spaced therefrom so as to receive the standard 11 therebetween as indicated particularly in Fig. 4. The movable section 41 of the presser foot has spaced bearings 45 and 46 rotatably mounted on the lower end of the guard and presenting a pair of flat faces 47 and 48 at right angles to each other and with which a flat leaf spring 49 may engage. The movable presser foot section 41 also has a projecting portion 50 serving as a handle and by means of which the section may be rotated about the axis of the guard and through approximately 90°. The presser foot when in operative position has the parts disposed as illustrated in Figs. 1, 2, 4, and 7 and with the rearwardly extending fingers 42 and 44 engaging with the standard. When it is desired to move the guard and presser foot laterally to expose the knife edge or the operating parts, the presser foot section 41 is rotated to the position indicated in Fig. 8 and in dotted lines in Figs. 3 and 4. This separates the finger members 42 and 44 and brings the

latter outwardly and forwardly to a position in front of the cutting edge of the knife so that the entire presser foot may swing laterally with the guard and cover plate. The spring 49 when engaging with the flat faces 48 holds the parts of the presser foot together as shown in Fig. 7 and when engaging with the flat faces 47 holds them spaced apart. By this construction of presser foot it will be noted that the lateral movement of the guard and presser foot for sharpening or other operation permits the return of the presser foot to its original position without effecting its vertical adjustment.

The standard 13 preferably has a cylindrical portion 51 threaded into an aperture in the base, and is made of very tough strong material to properly support the motor and the driving parts. The rear portion of this threaded lower end of the standard may lie substantially flush with the upper surface of the base 10 but the front part is preferably at a lower elevation than the upper surface of the base and carries a throat plate 52 which is of very hard material. This is substantially semi-cylindrical as indicated particularly in Fig. 9 and has a narrow slot 53 into which the lower end of the knife may enter. Preferably the throat plate slants upwardly somewhat from its front edge so as to slightly elevate the goods at the point where the cutting operation takes place. This throat plate may be secured in position in any suitable manner as for instance, by screws 54 extending up into it from the under side as indicated in Fig. 5.

By mounting the cover plate, guard, and presser foot as above described, the knife may be readily removed by unfastening it from the lug 21. The knife may then be taken out of the guiding groove of the standard 11 without dropping it down out through the bottom of the base 10 as is necessary in most constructions now in use. The placing of the axis of the motor at the righthand side of the plane of the knife plate not only permits of a better view of the cut of the material directly in advance of the cutting edge but also permits of a better application of the power of the motor. With the motor rotating clockwise from the position shown in Fig. 3, it will be noted that during the downstroke of the connecting rod 20 and the knife, the connecting rod is more nearly vertical than during the upstroke. Thus the power is more directly applied and with less lateral thrust on the guides 23 and 25. The greater lateral thrust during the upstroke is of minor consequence due to the fact that most of the work is done during the downstroke of the knife.

Having thus described my invention what

I claim as new and desire to secure by Letters Patent is:—

1. A cloth cutting machine, having a reciprocatory knife, a rotary driver, operative connections therebetween, a casing including a circular portion covering said driver and a depending portion rigid therewith covering said driver and said connections, and means for mounting said casing to permit rotation thereof about the center of said circular portion and the lateral swinging of said depending portion away from said knife.

2. A cloth cutting machine, having a reciprocatory knife, a rotary driver, operative connections therebetween, a casing having rigidly connected portions covering said driver and connections, and means for mounting said casing to permit lateral swinging of the portion covering said connection about the axis of said rotary driver and away from said knife.

3. A cloth cutting machine, including a reciprocatory knife, a motor casing presenting an annular flange, a rotary driver encircled thereby, a rotatable cover member for said driver having an annular flange telescoping with said first mentioned flange, and a knife guard carried by said cover and laterally movable away from said knife upon the rotation of said cover.

4. A cloth cutting machine, including a reciprocatory knife, a motor casing presenting an annular flange, a rotary driver encircled thereby, a rotatable cover member for said driver having an annular flange telescoping with said first mentioned flange, means for automatically retaining said cover plate in predetermined operative and inoperative positions, and a knife guard carried by said cover and laterally movable away from said knife upon the rotation of said cover.

5. A cloth cutting machine, including a reciprocatory knife, a motor casing presenting an annular flange, a rotary driver within said flange, operative connections between said driver and said knife, a cover member telescoping with said flange and having a depending portion covering said driving connections, and means for permitting limited rotary movement of said cover member about the axis of said driver but preventing movement axially thereof.

6. A cloth cutting machine, including a reciprocatory knife, a motor casing presenting an annular flange, a rotary driver within said flange, operative connections between said driver and said knife, a cover member telescoping with said flange and having a depending portion covering said driving connections, means for permitting limited rotary movement of said cover member about the axis of said driver but preventing movement axially thereof, and a knife guard carried by said cover member.

7. A cloth cutting machine, including a reciprocatory knife, a motor casing presenting an annular flange, a rotary driver within said flange, operative connections between said driver and said knife, a cover member telescoping with said flange and having a depending portion covering said driving connections, means for permitting limited rotary movement of said cover member about the axis of said driver but preventing movement axially thereof, and a knife guard carried by said cover member and adjustable endwise in respect thereto.
8. A cloth cutting machine including a motor, having a horizontal drive shaft, a reciprocatory knife, driving connections between said shaft and said knife, a cover member mounted to swing only in a plane normal to the plane of the knife and about a horizontal axis co-incident with the axis of said shaft, a knife guard carried by said cover member, and a presser foot carried by said guard and including two pivotally connected sections normally disposed upon opposite sides of the knife.
9. A cloth cutting machine, including a reciprocatory knife, a knife guard extending lengthwise thereof, means for mounting said guard to permit lateral swinging in a plane normal to the plane of the knife and on one side only thereof, and a presser foot having a pivoted member pivoted to swing into or out of operative position on the opposite side of the plane of the knife.
10. A cloth cutting machine, including a reciprocatory knife, a knife guard extending lengthwise thereof in front of the cutting edge, a presser foot carried thereby including a member substantially rigid with said guard for engagement on one side of the plane of the knife and a second section pivoted to said guard for engagement at the opposite side of said knife, and means for mounting said guard to permit swinging movement thereof in a plane normal to the plane of the knife when said second mentioned presser foot section is swung to inoperative position.
11. A cloth cutting machine, including a reciprocatory knife, a knife guard extending lengthwise thereof in front of the cutting edge, means for mounting said guard to swing only in a plane normal to the plane of the knife, and a presser foot section pivotally secured to the lower end thereof and movable into a position substantially parallel to said knife on the opposite side of the plane thereof when said guard is in operative position.
12. A cloth cutting machine, including a reciprocatory knife, a knife guard mounted to swing about a horizontal axis toward and from the plane of the knife, and a presser foot section carried by said guard and rotatable about an axis substantially parallel to and in front of the cutting edge and into or out of operative position alongside the knife, said presser foot section when in operative position serving to prevent the lateral swinging of said guard.
13. A cloth cutting machine, including a reciprocatory knife, a knife guard extending lengthwise thereof and in front of the cutting edge and mounted to swing in one direction only from normal position about a horizontal axis and in a plane normal to the plane of the knife, and a pair of presser foot sections carried thereby, one of said sections being pivoted to swing about a vertical axis in front of and substantially parallel to the cutting edge from a normal position alongside the knife to a position in front of the cutting edge to permit said swinging movement of said guard.
14. A cloth cutting machine, including an electric motor having a substantially horizontal drive shaft, a reciprocatory knife, driving connections between said knife and said shaft, a cover member for said driving connections and mounted to swing only in a plane at right angles to the plane of the knife to expose said driving connections, a knife guard carried by said cover member, and a presser foot having a pivoted section normally locking said guard and cover member against said swinging movement.
15. A cloth cutting machine, having a reciprocatory slide, a knife secured thereto, a guide rod projecting through said slide and along which the latter may move, a flange on said slide, a guide member engaging with said flange to prevent rotation of said slide about said rod, a drive shaft, and a pitman having eccentric connections to said shaft and pivoted to said flange.
16. A cloth cutting machine, having a reciprocatory slide, a knife secured thereto, a guide rod projecting through said slide and along which the latter may move, a flange on said slide, a guide member engaging with said flange to prevent rotation of said slide about said rod, a drive shaft having its axis at one side of the plane of said knife, and a pitman having eccentric connections to said shaft and pivoted to said flange.
17. A cloth cutting machine, including a reciprocatory knife, a slide secured thereto, a drive shaft rotatable about a horizontal axis at one side of the plane of the knife, a pitman connected to said slide and having eccentric connections to said shaft, a knife guard, and a cover member for said slide and carrying said knife guard and rotatable about the axis of said shaft to bring said guard into and out of operative position in respect to said knife and expose said slide.
18. A cloth cutting machine, including a reciprocatory knife, a presser foot including two members normally disposed upon oppo-

site sides of the plane of the knife and pivotally connected about a vertical axis in front of the cutting edge of the latter, whereby one section may be swung through 5 substantially 90° to a position in front of the edge of the knife, and means for supporting said presser foot and permitting of

the lateral movement thereof in a plane at right angles to the plane of the knife.

Signed at New York city, in the county of 10 New York, and State of New York, this 4th day of August A. D. 1919.

MARTIN ZAWISTOWSKI.
